DESIGN FOR A CHILD'S SLIPPER

Leon Goldberg, New York, N. Y.

Application August 5, 1935, Serial No. 57,943

Term of patent 3½ years

To all whom it may concern:

Be it known that I, Leon Goldberg, a citizen of the United States of America, residing in Manhattan, county of New York, and State of New York, have invented a new, original, and ornamental Design for a Child's Slipper, of which the following is a specification, reference being had to the accompanying drawing, forming part thereof, wherein,

I claim:

The ornamental design for a child's slipper, substantially as shown.

LEON GOLDBERG.
